UNITED STATES PATENT OFFICE.

GEORGE T. LADD, OF PITTSBURGH, PENNSYLVANIA.

WATER-TUBE BOILER.

1,130,745.

Specification of Letters Patent.

Patented Mar. 9, 1915.

Application filed January 22, 1914. Serial No. 813,779.

To all whom it may concern:

Be it known that I, GEORGE T. LADD, residing at Pittsburgh, in the county of Allegheny and State of Pennsylvania, a citizen 5 of the United States, have invented or discovered certain new and useful Improvements in Water-Tube Boilers, of which improvements the following is a specification.

The invention described herein relates to 10 certain improvements for the reception and segregation of solid impurities and insoluble elements from the water fed into boilers, said improvements being especially applicable to boilers of the vertical water tube 15 type.

The invention is hereinafter more fully described and claimed.

In the accompanying drawings forming a part of this specification, Figure 1 is an end 20 view of one of the drums of a vertical water tube boiler, a portion being broken away; Fig. 2 is a longitudinal section of the drum, and Fig. 3 is a sectional detail view on an enlarged scale.

As is the usual practice in this type of boiler, the lower ends of a plurality of tubes 2 are secured in any suitable manner in 25 openings in the drum 1, said tubes and drum together with an upper drum forming a 30 complete boiler unit. Water is fed into the drum 1 through one or more flanged nozzles 3, which are so arranged relative to one or more rows of tubes, that the ends of these tubes and the feed nozzles can be isolated 35 from the other tubes by a box 4. By thus inclosing the lower ends of the tubes and the feed nozzles in a common chamber, the feed water cannot mingle with the water in the boiler except by passing up through the 40 tubes connected to the chamber. In passing through the chamber and tubes the water is heated to a temperature sufficient to render most of the salts such as lime, magnesia, etc., insoluble. The water in the tubes connected 45 with this chamber is not materially agitated and although there will be a practically constant upward movement of the water this movement is slow, and the solid matter contained in the feed water including such as

is formed by heating the water will settle 50 down into the chamber, and can be blown out through the nozzles 3, which are adapted to be connected not only to the feed pipes but also to pipes for carrying away the sediment, etc. The removal of the sediment by 55 blowing-off is facilitated by arranging the nozzles 3 on a level with the lower wall of the box 4, as clearly shown in Figs. 1 and 3.

In order to facilitate access to the ends of the tubes connecting the chamber formed by 60 the box 4 and also to permit of the removal of such sediment as cannot be discharged through the blow-off, the box should be so attached to the inner wall of the drum that it can easily be detached or shifted. To this 65 end one side preferably the lower side of the box is attached to one of the members of hinges 5, the other members of the hinges being secured to the wall of the drum as clearly shown in Fig. 3. The box is held 70 in closed or operative position by any suitable means, such for example as the clips 6, which are so attached to the drum that one end will project over a flange 7 along the side of the box. These clips may be so constructed and attached to the drum that by merely loosening the nuts on the bolts the 75 clips can be turned out of engagement with the flange.

I claim herein as my invention:

1. The combination with a water tube boiler of a removable box arranged in one of the drums to inclose and isolate the ends of a portion of the tubes connected to said drum and the feed or blow-off nozzle. 80

2. The combination of a water tube boiler of a hinged box arranged within one of the drums to inclose and isolate the ends of a portion of the tubes connected to said drum and the feed or blow-off nozzle, and removable means for holding the box in closed position. 85

In testimony whereof I have hereunto set my hand.

GEORGE T. LADD.
